UNITED STATES PATENT OFFICE.

JAY L. KRAUS, OF CHICAGO, ILLINOIS.

DESIGN FOR A BANJO UKULELE.

Application filed September 29, 1926. Serial No. 19,201. Term of patent 7 years.

To all whom it may concern:

Be it known that I, JAY L. KRAUS, a citizen of the United States, residing at Chicago, in the county of Cook and State of Illinois, have invented a new, original, and ornamental Design for Banjo Ukuleles, of which the following is a specification, references being had to the accompanying drawing, forming part thereof.

Fig. 1 is a perspective view of a banjo-ukulele showing my new design, Fig. 2 is a side elevation thereof and Fig. 3 is a rear elevation thereof.

I claim:

The ornamental design for a banjo-ukulele as shown.

JAY L. KRAUS.
